UNITED STATES PATENT OFFICE.

LATHROP FRANK SMITH, OF COLUMBIANA, OHIO, ASSIGNOR TO FRANKLIN FURNITURE COMPANY, OF COLUMBIANA, OHIO, A CORPORATION OF OHIO.

DESIGN FOR A CHAIR OR SIMILAR ARTICLE.

Application filed April 7, 1928. Serial No. 28,171 Term of patent 3½ years.

To all whom it may concern:

Be it known that I, LATHROP FRANK SMITH, a citizen of the United States, residing at Columbiana, in the county of Columbiana and State of Ohio, have invented a new, original, and ornamental Design for a Chair or Similar Article, of which the following is a specification, reference being had to the accompanying drawing, forming part thereof.

The figure is a perspective view of a chair or similar article showing my new design.

I claim:

The ornamental design for a chair or similar article as shown.

In witness whereof, I hereunto subscribe my name, this 13th day of March, 1928.

L. FRANK SMITH.
